BY ATTORNEY.

UNITED STATES PATENT OFFICE.

CLARENCE A. EIGHMY, OF ERIE, PENNSYLVANIA, ASSIGNOR, BY DIRECT AND MESNE ASSIGNMENTS, TO THE ERIE SAFETY WINDOW COMPANY, OF SAME PLACE.

WINDOW FRAME AND SASH.

SPECIFICATION forming part of Letters Patent No. 620,023, dated February 21, 1899.

Application filed August 29, 1898. Serial No. 889,721. (No model.)

To all whom it may concern:

Be it known that I, CLARENCE A. EIGHMY, a citizen of the United States, residing at Erie, in the county of Erie and State of Pennsylvania, have invented certain new and useful Improvements in Window Frames and Sashes; and I do hereby declare the following to be a full, clear, and exact description of the invention, such as will enable others skilled in the art to which it appertains to make and use the same, reference being had to the accompanying drawings, and to the letters of reference marked thereon, forming part of this specification.

This invention relates to improvements in window frames and sash; and it consists substantially in so constructing the frame and sash that the sash can be quickly removed from the frame and replaced again at will and also so that the upper and lower sash can be independently locked in any desired position. These results are accomplished by making vertical grooves in the sides or jambs of the frame and like vertical grooves in the edges of the sash, in which are placed strips of wood or metal which are provided with notches in their front edges to engage removable bolts for securing them to the sash and with notches in their rear edges adapted to be engaged by locking-bolts in the window-frame. The upper ends of these strips are also provided with openings to which sash-cords can be secured, these and other features of the invention being hereinafter fully set forth and described, and illustrated in the accompanying drawings, in which—

Figure 1 is a front view in elevation of a window-frame and sash embodying this invention, parts thereof being broken away. Fig. 2 is a horizontal section of the same on the line $x-x$ in Fig. 1 looking in the direction of the arrow. Fig. 3 is a vertical section of the window-frame on the line $y-y$ in Fig. 1 looking in the direction of the arrow. Fig. 4 is an enlarged view in elevation of one edge of the sash. Fig. 5 is an enlarged side view in elevation of one of the strips adapted to be secured in the groove in the sash. Fig. 6 is a view in elevation of the front edge of the

same. Fig. 7 is a perspective view of a bolt 50 for locking the upper sash. Fig. 8 is a like view of a bolt for locking the lower sash.

In the drawings thus illustrating this invention, A is a window-frame the jambs A' of which are preferably constructed with projections a the width of the edges of the upper sash B, against which the edges of the upper sash B contact and which form outside stops for the lower sash C.

In the faces of the jambs A', I cut vertical 60 grooves $a'-a^2$, in the upper edges of which sash-cord pulleys $d-d$ are secured in the usual manner.

In the edges of the upper and lower sashes B and C there are vertical grooves b , corresponding to the grooves $a'-a^2$ in the window-jambs.

In the grooves $a'-a^2$ I place strips E of metal or wood, Figs. 5 and 6, to the upper ends of which sash-cords F are secured. These strips 70 E are placed in the grooves $a'-a^2$, so that the edges e thereof project outward from the jambs A', so that the edges will enter the grooves b in the sashes B and C, as illustrated in Fig. 1, and when placed therein they are 75 secured from vertical movement in the sashes by means of short pins or bolts b' , which enter holes c in the inside faces of the sash B and C and pass through the notches e' in the strips E, these pins or bolts b' being removable at will, so that the strips E can be raised up out of the sashes B and C or either of them and the sash or sashes removed from the window-frame A at pleasure and can be at once replaced and secured by sliding the strips E 80 back into the grooves b and securing them therein by means of the pins or bolts b' . In the rear edge of the strips E there are notches e^2 , with which bolts G and H, Figs. 7 and 8, passing through holes g and h in the window- 90 casing A², engage, by means whereof the sashes B and C can be locked in any position.

It will be observed that no stops are used on the inside of either sash, as they are held in place wholly by means of the strips E, fitting in the grooves $a'-a^2$ in the jamb and in the grooves b in the edges of the sash.

I have thus described this invention so as

to enable others to construct and use the same; but I am aware that many modifications of the same can be readily made without departing from the spirit of the invention. Therefore

5 5. What I claim as new, and desire to secure by Letters Patent of the United States, is—

1. The combination of window-jambs having vertical grooves therein, window-sash having vertical grooves in the edges thereof, removable strips fitting in the grooves of the sash and having notches in both edges thereof, removable pins in the sash engaging a notch in one edge of the strips so as to secure them in the sash, and transversely-sliding bolts in
- 10 15 the window-frame adapted to engage the notches in the other edge of the strips, substantially as and for the purpose set forth.

2. The combination of a window-frame A,

having projections a on the faces of the jambs A' against which the upper sash B in said frame operates, and grooves a' a^2 in said jambs, upper and lower sash B and C having grooves b in the edges thereof, strips E having notches e' in the front edges thereof adapted to be engaged by pins b' when in place in the grooves b in the sash, and having notches e^2 in their rear edges and locking-bolts G and H in the window-frame jambs adapted to engage the notches e^2 in said strips, substantially as and for the purpose set forth. 20 25 30

In testimony whereof I affix my signature in presence of two witnesses.

CLARENCE A. EIGHMY.
